CONDIMENT SHAKER

Max A. Weisbrot, Chicago, Ill.

Application June 26, 1950, Serial No. 10,758

Term of patent 14 years

(Cl. D44—22)

To all whom it may concern:

Be it known, that I, Max A. Weisbrot, a citizen of the United States, residing at Chicago, in the county of Cook and State of Illinois, have invented a new, original, and ornamental Design for a Condiment Shaker, of which the following is a specification, reference being had to the accompanying drawing, forming part thereof.

Fig. 1 is a side elevational view of a condiment shaker, showing my new design;

Figs. 2 and 3 are views similar to Fig. 1 showing the article rotated 90° and 180°, respectively, with respect to Fig. 1; and

Fig. 4 is a top plan view thereof.

I claim:

The ornamental design for a condiment shaker, substantially as shown.

MAX A. WEISBROT.
